(57) CLAIM

The ornamental design for a beach towel and poncho, as shown and described.

DESCRIPTION

FIG. 1 is a plan view of the beach towel and poncho.

FIG. 2 is a detail of the closed neck opening in the beach towel and poncho.

FIG. 3 is a detail showing the neck opening in the beach towel and poncho.

FIG. 4 shows the front view of the beach towel and poncho on a person.

FIG. 5 shows the back view of the beach towel and poncho on a person.

FIG. 6 shows the side view of the beach towel and poncho in an open position on a person; and,

FIG. 7 shows the side view of the beach towel and poncho in a closed position on a person.

The broken line showing of the human figure is for illustrative purposes only and forms no part of the claimed design.
